CLAIM

We claim, the ornamental design for a syringe with safety mechanism, as shown and described.

DESCRIPTION

FIG. 1 is an enlarged front perspective view of a syringe with safety mechanism showing the claimed design; FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged view of the encircled portion 8 of FIG. 2;

FIG. 9 is an enlarged view of the encircled portion 9 of FIG. 5;

FIG. 10 is a cross-sectional view taken along line 10-10 of FIG. 8;

FIG. 11 is a front view of the syringe with safety mechanism which the safety mechanism is in first moved position with the needle exposed;

FIG. 12 is a front view of the syringe with safety mechanism which the safety mechanism is in a second moved position with the needle retracted; and,

FIG. 13 is a front view of the syringe with safety mechanism which the safety mechanism is in third moved position with the needle retracted and prevented against exposure.
